UNITED STATES PATENT OFFICE

HEYMAN ROSENBERG, OF NEW YORK, N. Y.

HEAT TREATING APPARATUS FOR METAL WORK

Application filed December 10, 1931. Serial No. 580,158.

This invention relates to improvements in apparatus for heat treatment of articles of work, and more particularly to the general type of apparatus set forth in my co-pending application for U. S. Letters Patent filed September 17, 1931, Serial No. 563,426, for art and apparatus for treating and handling articles of work, and in the several co-pending applications therein referred to.

The essential object in view is the successful and effective heat treatment of articles of work in a minimum time by apparatus adapted for operation with a sufficiently reduced requirement for manual manipulations to enable a single operator to carry on the work of heat treatment.

A more detailed object is the retention of the work being treated within the heat treating area for the requisite time without appreciable reduction in the rapidity with which fresh supplies of work may be introduced and treated supplies removed, and in further detail it is an object of the present invention to prevent delay or interference through inaccuracy or lack of precision in the location of batches of work during positioning thereof within the heating area.

In still further detail, it is an object of the present invention to move work within the heat treating area with a step by step movement and to effect a braking action for bringing the work to a standstill between steps at a predetermined point, the actuating and braking mechanisms being operated by synchronized mechanism for effective coordination.

Another detailed object is the automatic removal of a batch of work from a place of discharge for insuring against obstruction for the next successive batch.

With these and other objects in view as will in part hereinafter become apparent and in part be stated, the invention includes means for heat treating work, power driven means for moving work within the heat treating area, and means for shifting batches of work to and from the heat treating area.

The invention also comprises a rotary sup-

port for work adapted to detachably sustain work in a heat treating area, means for rotating the rotary support, and brake mechanism synchronized therewith for braking the movement of the rotary support against 55 coasting for providing precision in the stopping points thereof.

The invention includes also in such a combination means for enabling manual adjustment of the rotary support in case inaccuracy of location of stop occurs.

The invention still further includes in such a combination a hood substantially enclosing the heat treating area and through which hood the actuator of the rotary support extends.

The invention still further comprises discharging means for work, and a conveyor cooperating therewith for removing work from the conveyor while the work is receiving 70 the concluding heat treating action.

The invention comprises certain other novel constructions, combinations, and arrangements of parts as will in part herein-after become apparent and in part be pointed out and will be thereafter set forth in the appended claims.

In the accompanying drawings,—

Figure 1 is a sectional elevation of an apparatus embodying the features of the present invention, parts being broken away for the saving of space.

Figure 2 is a top plan view thereof, parts being broken away for disclosing parts beneath, and other parts being broken away 85 for the saving of space.

Figure 3 is a transverse section taken substantially on the plane indicated by line 3—3 of Figure 1, and looking in the direction of the arrow, parts being seen in elevation.

While the present invention is illustrated as applied to the molten bath treatment of metal articles, as, for instance, for cyanide case-hardening, and by way of illustration 95 this particular treatment will be hereinafter specifically referred to, it should be understood that the apparatus is well adapted for various other heat treatments, such as molten metal annealing, direct heat annealing, 100

and other metal work treatment whose requirements are known and are within the capacity of the apparatus. Thus, the reference to cyanide case-hardening treatment 5 and to the cyanide bath is intended to include any appropriate heat treatment within the capacity of the structures disclosed in the drawings and hereinafter described and claimed, and such reference is to be taken 10 as illustrative only.

Referring to the drawings by numerals, 1 indicates any appropriate furnace supplied 15 with fuel of any acceptable type not illustrated, one very effective form of fuel being gas. Pendent from the top of and within the furnace 1 is the pot 2 which surrounds the heating area for the high temperature heat treatment of the work and which contains the molten mass 3 of cyanide or other 20 liquid, according to the treatment being carried out.

A bed plate or frame 4 is provided with a downwardly-extending shaft 5 journaled in an appropriately anchored standard or support 6, and preferably detachably connected thereto, the shaft 5 being journaled to oscillate about a vertical axis and being provided with an actuating gear 7, preferably of the worm gear type, meshing with a 25 worm 8 carried by and adapted to be actuated through an appropriate shaft 9 journaled in a bracket 10 connected to the support 6. By means of the shaft 9, worm 10, and gear 7, the bed plate 4 is adapted to be 30 swung with the shaft 5 about the axis of the shaft to and from a position where the free end of bed plate 4 rests on a standard or support 11. Preferably formed integral and upstanding from bed plate 4 is a stand- 35 40 45 50 55 60 65 70 75 80 85 90 95 100 105 110 115 120 125 130 135 140 145 150 155 160 165 170 175 180 185 190 195 200 205 the grooves of the spirals and being caused to travel along the conveyors 34 by the camming action of such spirals. The gearing 36 is so located as to cause the spirals 34 to rotate relatively in opposite directions and actually toward each other, so that there is no tendency to shift the rods 21 longitudinally since the frictional sliding contacts of the two ends oppose each other.

10 Between the furnace and vat is arranged a shifting or delivery lever and actuating mechanism which is preferably substantially identically the same as that set forth in my above-identified co-pending application 15 except that the operating lever is preferably made of a pair of parallel arms spaced to accommodate the load movement therebetween instead of depending upon a single arm. In greater detail, the transfer mechanism 20 preferably consists of a rock shaft 39 journaled in appropriate brackets 40 fixed to an outstanding part of the cover of furnace 1 and carrying an appropriately keyed or otherwise fixed rocker arm made up of 25 parallel bars 41, 41, spaced apart sufficiently to accommodate a batch of work therebetween. The free ends of the bars 41 are connected by a fixed rod 42 on which is freely pivotally mounted a pair of pendent hooks 33, spaced apart sufficiently to accommodate the shank of hook 22 therebetween, the hooks 43 being proportioned to effectively receive and sustain the cross bar 21 of each hook 22. Hooks 43 are preferably connected together 25 and held by an appropriate stop against lateral shifting, and are provided with a counterbalance 44 for retaining the hooks proper out of the vertical line of the axis of their pivot, so that, when a load is sustained by the hooks, the weight of the load will cause the hooks to lie in said vertical line, and, when the load is relieved from the hooks and the hooks are lowered to be free of the load, the counterbalance weight 44 will swing the hooks laterally of the vertical line of the axis of pivotal movement of the hooks and thus leave the hooks free to escape from engagement with the load, that is with the cross bar 21 which represents the load, since it is the means of connection of a batch of work to the hooks. Shaft 39 is preferably counterbalanced at 45 to render actuation of the shaft comparatively easy, and the shaft carries an appropriate gear within a gear housing 46, which gear is connected through a chain of gears also arranged in said housing to an actuating shaft 47 which carries the hand operating crank 48. Crank 48 may, and preferably does, 50 consist of a series of bars each serving as a crank to facilitate manual actuation. The detailed construction of the gears within housing 46 is not illustrated, since it is fully shown in my co-pending application filed 55 September 11, 1931, Serial No. 562,394.

While the driving mechanism for shaft 16 is susceptible of a wide range of variation, one preferred embodiment is illustrated in the accompanying drawings and includes an actuator or electric motor 49 connected 70 to actuate appropriate reducing speed gears arranged in housing 50 and not specifically illustrated, which reducing speed gears actuate the power shaft 51 carrying and driving the cam disc 52. Shaft 51 extends 75 through and is journaled in bracket 53, and also carries the driving cam disc 54.

A reciprocating link 55 is provided with a finger 56 (see Finger 1) extending into the cam groove in the face of cam disc 52 80 and is actuated thereby to impart the requisite thrusts to the link for the purposes intended, cooperating with the action of the cam of disc 54. The upper end of the link 55 is pivotally connected to a bell crank 85 lever 57 which is connected by link 58 to the reciprocating rod 59 slidably mounted in an appropriate bracket 60. The opposite end of rod 59 from that engaging link 58 is provided with a disc brake 61 cooperatively disposed with respect to an appropriate braking drum 62 carried by the free end of the rear section of shaft 16, so that, when the cam of disc 52 is in the proper position, the brake 61 engages drum 62 and effects stopping of the movement of table 19 and prevents coasting thereof. The bell crank lever 57 is preferably offset, as seen in Figure 2 and indicated in Figure 3, the arms of the lever being connected by an 90 appropriately journaled shaft 57'.

The cam disc 54 is provided with a cam groove 63 into which the finger 64 of reciprocating link 65 extends. Links 65 is 105 guided in an appropriate sleeve 66 carried by a part of the upstanding framework 67 mounted on the bed plate 4. Pivoted to link 65 is a link 68 which in turn extends between and is pivotally connected to a pair of oscillating blocks 69 journaled on the rear section of shaft 16. A ratchet wheel 70 is 110 fixed to the shaft 16 between the blocks 69 and is engaged by a pawl 71 stressed by spring 72 fixed to the blocks 69 in position for retaining pawl 71 in engagement with ratchet wheel 70. The contour of cam groove 63 (see Figure 3) is such as to impart to links 65 and 68 and blocks 69 the requisite reciprocation for causing the pawl 71 to move the length of one tooth of ratchet 70 with each revolution of cam discs 52 and 54, and to drop from one tooth to the next so that, as the cam disc 54 is revolved, the shaft 16 is given a step by step movement, which movement is imparted to the table 19 and the parts are located and the stroke of the step measured to cause a batch of work to exactly move into line with the hooks 43 with each advance stroke of pawl 71. While the pawl 71 is making its return stroke, and 115 120 125 130 135 140

is pausing at the end of the return stroke by virtue of the concentric portion of cam 63, the table will remain motionless and afford the operator opportunity to unload 5 and reload the particular yoke of the table presented, as hereinafter more specifically set forth. As the pawl 71 reaches the limit of its advance stroke, the brake 61 seats itself against brake drum 62 and remains 10 seated until the pawl 71 is ready for its next advance stroke, and then, as the pawl 71 begins its next advance stroke, the brake 61 moves away from drum 62 and leaves the table 19 free to move forward through its 15 next step.

While, of course, the manual features of the operation are susceptible of quite a range of variation, the preferred operation will be carried out as follows:

- 20 The table 19 will be loaded by manually swinging lever 41 over toward, but not to, the dotted line position of Figure 1, that is to a position where a batch of work 24 resting on the platform 33 can be readily lifted 25 manually to cause the bail of such batch of work to drop into the hook of the carrier bar 21 previously supplied to hooks 43 by the operator. The operator then rotates crank lever 48 to cause contra-clockwise 30 movement of lever 41. The batch of work being suspended vertically will move between the bars 41 as they swing toward the full line position of Figure 1, and further downward movement of the lever 41 will 35 cause the cross bar 21 with its suspended load to rest upon the predetermined yoke 20. The lever 41 is then lowered just a slight distance sufficient to allow the counterbalancing force of weight 44 to swing hooks 40 43 out of the line of the respective bar 21, and then the lever 41 is swung back to receive another batch of work while table 19 advances a step to present an empty yoke 20. This is continued until the entire group of 45 yokes 20 is full. Meanwhile, it should be understood that the work first introduced will have received the requisite cyanide, or other desired heat treatment, and when the first introduced batch of work reaches a position again in line with hooks 43, after rotation within the pot 2, the operator lowers the lever 41 above the pot with the hooks in an empty condition, and when the hooks have reached a position beneath the line of 50 the respective cross bar 21, the operator will manually press the hooks 43 sufficiently to overcome the counterbalance weight 44 and to move to a position beneath cross bar 21. While the hooks are held in this position, 55 the operator moves lever 48 for lifting lever 41 to bring the hooks into engagement with the cross bar, and then lever 48 is further moved to swing the cross bar through the arc indicated by the dot and dash line 60 in Figure 1 to the position indicated by 65

dotted lines in said figure. It should be understood that the manual movement of the hooks 43 against the counterbalancing pressure of weight 44 may be accomplished in any preferred manner, one appropriate means consisting in the use of a rod in the left hand of the operator while the right hand of the operator actuates the lever 48. Any other appropriate means may be employed, and it is, of course, possible, when desired, to provide automatic means, such as a shifting cam, for shifting the location of weight 44 and changing its center of gravity. When the parts reach the position of the dotted lines in Figure 1, the cross bar 21 engaging the conveyor spirals 34 will move in a direction away from the furnace, and the operator, of course, as a continuous movement, will move lever 41 downward sufficiently to free the hooks 43, and as soon as they are free will bring them back up to the loading position, which is only sufficiently above the platform 33 to render manual loading easy and convenient. A new batch of work is then suspended on the hooks 43, and the lever returned to deliver the load to the now empty yoke of table 19. Weight 44 effects an automatic release with this delivery, and the operator then lifts lever 41 slightly but sufficiently to allow the next step of the table 19 to present the next batch of work to be removed, thus completing the cycle of operations. It should be understood, of course, that the operator must work with such speed and dexterity as to 100 reload and get the hooks 43 out of the path of the table 19 during the time the pawl 71 is moving back and pausing preparatory for a new actuating stroke. The timing of the motor 49 and the reducing speed gears 50 will be such as to afford the requisite time for operations. If any mishap should occur, or any occasion arise to desire the table 19 not to make an advance step on time, the operator merely manually opens the clutch 18, and the table 19 will thereupon remain stationary until either actuated by gear 29 or the clutch 18 is returned to operative position.

The batches of work in the vat 32 may be 115 removed therefrom in any preferred manner, as by manual removal at the remote end of the vat.

It is well understood that fumes incident to heat treatment of metal work, and particularly so when cyanide is used, are not only obnoxious, but are dangerous to the health, and it is one of the objects of the present invention to largely avoid opportunity for the release of fumes, so that what few fumes do escape may be easily eliminated by hooded ventilators. To this end, the space above the pot 2 is covered by a cap 73 completely enclosing the pot and having a flange resting on and preferably 125

detachably fixed to the top of the furnace 1. The cap 73, being of a very substantial size, is preferably made up of separable segments of sheet metal, and the inner face is preferably lined with asbestos, or other appropriate heat and fumes resisting substance 74. The cap 73 is centrally apertured to accommodate shaft 14 and its connected parts, and a detachable collar 75 is preferably bolted, or otherwise fixed to the cap 73, and depends down to approximate contact with the upper surface of table 19, a slight but sufficient space being left therebetween to allow free rotation of the table without friction. But for the necessity for access to the pot, the fumes would thus be practically completely sealed against escape. To allow movement of batches of work into and out of the pot, the cap 73 is formed with an appropriate aperture 76 of sufficient width and length to accomodate parts to be moved therethrough.

It will be noted that while the worm 8 is stationary, it serves as a lock to hold worm gear 7 against movement, and, therefore, tends to lock the superimposed parts in the required fixed position, but as a means of further insurance against accidental or other undesired displacement, overlapping flanges 77 and 78 respectively from the upright 12 the top of furnace 1 are detachably fastened together by bolt 79. Should it become desirable for any reason to gain full and free access either to the pot 2 or to the interior of furnace 1, or to replace the table 19, or treat otherwise inaccessible parts thereof, the cap 73 with its collar 75 are removed after the table 19 has been fully discharged, and then the bolt 79 is withdrawn and the worm 40 actuated to swing the superimposed parts laterally with respect to the furnace 1 until the table 19 is entirely clear of the furnace. After the desired interchange, repair or other treatment, the parts are restored for 45 further operation.

What is claimed is:—

1. In apparatus of the class described, the combination, with means providing a heating area, of a work support arranged above the heating area, means for advancing the work support with a step by step movement, and braking means for the work support for stopping movement of the work support at a definite predetermined location, and releasing the work support for free movement at other times.

2. The combination as claimed in claim 1 herein the moving means and braking means are mechanically connected to cooperate in synchronism to apply the brake only at the conclusion of the step of movement under the force of the moving means.

3. The combination as claimed in claim 1 wherein the moving means and braking means are mechanically connected to coop-

erate in synchronism to apply the brake only at the conclusion of the step of movement under the force of the moving means and the step by step movement is rotary.

4. In apparatus of the class described, the combination, with means providing a heating area, of a supporting table substantially centrally above the area, a shaft rotatably mounted and sustaining the table suspended in position, means for driving the shaft, and clutching means for interrupting the driving connection with the shaft.

5. In heat treating apparatus, the combination, with means providing a heat treating area, and means adjacent to the first-mentioned means providing a further heat treatment area, of a spiral conveyor comprising spaced spirals disposed above the said further heat treatment area and adapted to receive in the grooves of the spirals the cross bar of work sustaining means while such work sustaining means suspends the work in the further heat treatment area, and means for shifting work thus carried by work supporting means from the first-mentioned heat treatment area to the further heat treatment area into such engagement with said spirals.

6. In apparatus of the class described, the combination, with means providing a heating chamber, of a work carrier adjacent to and cooperating with the heating chamber and movably mounted relative thereto for moving work therein, a shaft for moving the work carrier, a pawl and ratchet actuator for the shaft, and a brake for the shaft geared to assume and maintain the braking position only during return movement of the pawl.

7. In apparatus of the class described, the combination, with means providing a heating area, of work supporting and moving means located for sustaining work in cooperative relation to said heat treating area, means for moving the work support, a brake for braking movement of the work support, and means for moving the brake into and out of braking relation for leaving the work support free for movement at times and at other times stopping movement thereof.

8. The combination as claimed in claim 7 wherein the brake operating means is timed with respect to the movement of the work supporting means to effect braking action only between the successive steps of work positioning movement of the supporting means.

In testimony whereof I affix my signature.
HEYMAN ROSENBERG.
